CLAIM

The ornamental design for a cylindrical pouch with straw hole, as shown and described.

DESCRIPTION

FIG. 1 is an elevated perspective view of a first embodiment of a cylindrical pouch with straw hole showing my new design;

FIG. 2 is a first side view thereof;

FIG. 3 is a second side view thereof;

FIG. 4 is a top view thereof;

FIG. 5 is a bottom view thereof;

FIG. 6 is a front view thereof;

FIG. 7 is a rear view thereof;

FIG. 8 is an elevated perspective view of a second embodiment of a cylindrical pouch with straw hole showing my new design;

FIG. 9 is a first side view thereof;

FIG. 10 is a second side view thereof;

FIG. 11 is a top view thereof;

FIG. 12 is a bottom view thereof;

FIG. 13 is a front view thereof; and,

FIG. 14 is a rear view thereof.
